UNITED STATES PATENT OFFICE.

JOHN W. TUMALTY, OF CHICAGO, ILLINOIS.

MILK-BOTTLE HOLDER.

Application filed October 10, 1921. Serial No. 506,842.

To all whom it may concern:

Be it known that I, JOHN W. TUMALTY, a citizen of the United States, and a resident of the city of Chicago, county of Cook, and State of Illinois, have invented certain new and useful Improvements in Milk-Bottle Holders, of which the following is a specification.

My invention relates to improvements in milk bottle holders, and has for its object the provision of an improved construction of this character by means of which the theft or unauthorized removal of milk bottles and the like is prevented.

Other objects will appear hereinafter.

The invention consists in the combinations and arrangements of parts hereinafter described and claimed.

The invention will be best understood by reference to the accompanying drawings forming a part of this specification, and in which,

Fig. 1 is a top plan view of a milk bottle holder embodying the invention,

Fig. 2 is an interior elevation of the same, and

Fig. 3 is an end view of the same.

The preferred form of construction as illustrated in the drawings comprises a sheet metal casing 4 divided by a central partition 5 into two separate compartments. The casing 5 is provided in its rear wall with screw openings for the passage of screws 6 and a cover plate 7 is laterally slidably in said casing to cover said screws. An opening 8 is provided in one end of the casing 4 to permit of the insertion and removal of said cover plate 7 and a screw 9 is passed through said cover plate to secure the same in place. The casing 4 is secured to the outer side of an ordinary inwardly swinging door 10 adjacent the door frame 11 at the hinged end thereof and opening 8 is adjacent the door frame so that when the door is closed it is impossible to remove the cover plate 7 and the casing 4.

The casing 4 is provided with an upwardly swinging angular closure 12 constituting the outer side and the outer portion of the top of said casing, said closure giving access to said casing for the insertion of the necks of milk bottles therein. The closure 12 carries a spring latch 13 adapted to engage a notch 14 in a lock plate 15 secured to the door frame 11 in operative relation with the casing 4 as shown. The lock plate 15 is pro-

vided with a guard flange 16 permitting of free swinging of the closure 12 but preventing tampering with the latch 13. Notches 17 are provided in the bottoms of the compartments of casing 4 and are adapted to receive the necks of milk bottles 18 as indicated.

In use the closure 12 is swung upwardly and the door closed, thus leaving the holder ready for the insertion of the bottles by the milkman. When the bottles are inserted by the milkman he simply swings the closure 12 downwardly until the latch 13 snaps into the notch 14 whereupon the removal of said bottles is prevented. When the door is opened the latch 13 is withdrawn from the notch 14 permitting of the ready removal of the milk bottles. This specific form and arrangement of parts is a simple and effective one for the purpose.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. The combination with a swinging door, of a casing mounted on said door having a supporting member provided with a notch open at an edge thereof and permitting lateral insertion of the neck of a bottle; and locking means preventing removal of said bottle while the door is closed but permitting lateral removal when the door is open, substantially as described.

2. The combination with a swinging door, of a casing mounted on said door and provided in the bottom with a notch open at an edge of the bottom and permitting lateral insertion of the neck of a bottle; and locking means preventing removal of said bottle while the door is closed but permitting lateral removal when the door is open, substantially as described.

3. The combination with a swinging door of a casing secured to said door adjacent the hinged side thereof; a swinging closure for said casing, there being a notch in the bottom of said casing permitting insertion

of a bottle neck therein and suspension of the bottle from said casing; a spring latch on said closure; and a lock plate secured to the door frame in operative relation with said casing and provided with means for receiving said latch and holding said closure closed when the door is closed but releasing said closure when the door is open, substantially as described.

- 10 4. The combination with a swinging door of a casing secured to said door adjacent the hinged side thereof; an upwardly swinging closure for said casing; a spring latch on said closure; a lock plate secured to the door frame in operative relation with said casing and provided with a notch to receive said latch and hold said closure closed when the door is closed but releasing said closure when the door is opened; screws securing said casing to said door; and a cover plate for

said screws, laterally slidable in said casing, there being an opening in said casing for the insertion of said cover plate adjacent the door frame, substantially as described.

- 5 5. The combination with a swinging door, 25 of a casing mounted on said door; screws securing said casing to said door; and a cover plate for said screws slidable in said casing, there being an opening in said casing adjacent the door frame permitting of insertion 30 of said cover plate, substantially as described.

In testimony whereof I have signed my name to this specification in the presence of two subscribing witnesses.

JOHN W. TUMALTY.
